UNITED STATES PATENT OFFICE.

CORA N. LITTLEHALE, OF EL PASO, TEXAS.

DESIGN FOR A FLOWER-HOLDER FOR PERSONAL WEAR.

SPECIFICATION forming part of Design No. 30,653, dated May 2, 1899.

Application filed April 8, 1899. Serial No. 712,327. Term of patent 7 years.

To all whom it may concern:

Be it known that I, CORA N. LITTLEHALE, a citizen of the United States, residing at El Paso, in the county of El Paso and State of Texas, have invented and produced a new and original Design for a Flower-Holder for Personal Wear; and I do hereby declare the following to be a full, clear, and exact description of the invention, such as will enable others skilled in the art to which it appertains to make and use the same.

My invention relates to a flower-holder to be worn upon the person.

The design consists, essentially, of a hollow transparent vessel or body having a flaring mouth with serrated edge and an introverted lip or rim, the rear side of the mouth being higher than the front and of less violent curvature, and when viewed from the front the opening in the mouth and the whole surrounding edge being seen in the form of an ellipse whose greatest diameter is in a plane transverse to the body of the vessel, the said body being tapered and bent toward a relatively small point in a parabolic curve and being elliptical in cross-section, its greatest diameter being in the plane of the curvature thereof, the said body having two peripheral grooves at some distance apart, the one being near the larger end of the body and being circled by what appears to be a small continu-

ous band embedded in said grooves and which extends from one groove to the other and terminates in a point, all as seen in the accompanying drawings.

In the accompanying drawings, which show a flower-holder embodying my design, Figure 1 is a rear elevation. Fig. 2 is front elevation; and Fig. 3 is a section taken on the line 3 3 in Fig. 2, looking to the left.

1 indicates the vessel or body having flaring mouth with serrated edge 2 and introverted lip or rim 3. The peripheral grooves are seen at 4 and 5 in Figs 1 and 2, and the element having the appearance of fine wire encircling said body within said grooves is seen at 6 and 7, the portion extending from one groove to the other and intersecting the lower groove and terminating in a sharp point being seen at 8.

The body of the vessel is ornamented to simulate a flower in full bloom.

What I claim is—

The design for a flower-holder for personal wear, substantially as herein shown and described.

In testimony whereof I affix my signature in presence of two witnesses.

CORA N. LITTLEHALE.
